UNITED STATES PATENT OFFICE

157,377

EXTENSION TABLE

Max S. Karp, Los Angeles, Calif.

Application February 20, 1948, Serial No. 144,633

Term of patent 3½ years

(Cl. D33—14)

To all whom it may concern:

Be it known that I, Max S. Karp, a citizen of the United States, residing at Los Angeles, in the county of Los Angeles and State of California, have invented a new, original, and ornamental Design for an Extension Table, of which the following is a specification, reference being had to the accompanying drawing, forming part thereof.

Fig. 1 is a perspective view of an extension table, in closed condition, showing my new design.

Fig. 2 is a perspective view thereof as seen from the end and showing the opposite side.

Fig. 3 is a perspective view showing the table in open condition.

I claim:

The ornamental design for an extension table, substantially as shown.

MAX S. KARP.
